[57] ABSTRACT

An oil delivery system wherein, in order to effect the discharge of solidified or semi-solidified oil remaining in a tank after primary delivery of the bulk of the oil therefrom, a nozzle is inserted in the free space within the tank, oil of the same kind as the oil in the primary delivery is heated and directed through the nozzle onto the residual oil, which is thereby melted, and rendered easily movable.

5 Claims, 3 Drawing Figures

FIG. I

FIG. 2

FIG. 3

DELIVERY SYSTEM FOR HIGH MELTING POINT OILS IN A TANK

The present invention relates to an oil delivery system for oils having a high melting, and more particularly to an oil delivery system for the discharge of solidified or semi-solidified oil, which is of special advantage in secondary, or final evacuation of high melting point oils, or similar substances, held in a solidified, or semi-solidified state in a tank, and wherein a nozzle, or nozzles are inserted into a tank, or similar container holding residual, solidified or semi-solidified oil which it is desired to discharge, and oil that has been previously discharged from the tank, or the same type of oil from another source, is projected through the nozzle, or nozzles onto the residual oil, whereby the residual oil is melted and made easily removable from the tank.

Bulk transport of oil is normally effected by ships that are equipped with suitable tanks, and oil is generally delivered therefrom by being pumped out. When oil in a tank is solidified or semi-solidified, as is often the case with beef tallow, coconut oil, or highly viscous mineral oils, it is general practice to first melt the oil by means of a heater provided in the tank, and then pump the oil out. However, this method of delivering solidified or semi-solidified oil is only effective for mammoth tankers, or similar large vessels with double bottoms, and is not feasible for coastal vessels used for oil transport, which are mostly single-bottomed. When oil is piped from these smaller vessels, a considerable amount of oil, which has been cooled by the surrounding water, remains solidified in the tank especially on the bottom of the tank and the sides of the tank between the bottom and the water-line, and the only way this residual oil can be removed is by buckets, shovels, and manual labour. This method of removal of residual oil is obviously undesirable from the point of view of health of persons employed in this task, since the work is rendered arduous by the fact that the internal contour of the oil tank, that is, the ship's hold, comprises many projections, and since the inside of the tank is malodorous and hot. Also, the method has considerable administrative and economic disadvantages, since it is not always easy to assemble the required labour force, and labour costs of a force assembled for this purpose are disproportionately high compared with labour costs of normal staff. Another disadvantage and undesirable feature of this conventional method is that it is extremely difficult to effect removal of the entirety of the residual oil, and even after manual cleaning of the tank, there is still some oil left, which is discharged into the sea after final washing of the tank, thus contributing to environmental pollution.

Furthermore, in relation to oil delivery, it is also to be noted that there have been known many inventive systems for cleaning the oil tanks of tankers or bulk cargo vessels which essentially involve spraying the insides of tanks with sea water, cleaning water, superheated steam, or treated oil. In the employment of these conventional systems, secondary unloading (that is, discharge of residual oil left in a tank after primary unloading of the bulk of the oil) is generally not effected, but the residual oil is washed out during the cleaning process and ejected into the sea. Even though this residual oil is only a certain fraction of the total oil held in a tank, it nevertheless represents an unjustifi-

able waste and economic loss, and an intolerable pollution of the sea.

A solution to this problem has become more and more urgent in view of the increased concentration of industry on the sea-board and the daily increase in oil requirements.

This problem is not of course limited to sea-transport of oil, but is also present with regards to inland transport and storage of oil.

10 It is accordingly an object of the present invention to provide an oil delivery system offering economical, rapid, and total evacuation of oil from a bulk storage or transport tank, or similar container and delivery thereof to another container.

15 It is a further object of the invention to provide an oil delivery system that, unlike conventional systems, does not demand recourse to manual labour for the removal of residual oil in a tank.

Another object of the invention is to eliminate a factor 20 of environmental pollution that is conventionally inherent in oiling stations.

A still further object of the invention is to provide an oil delivery system wherein only the oil it is desired to discharge and obtain for later use is evacuated from a tank and wherein the employment of sea water, washing water, treated oil, or similar substances is not required, thereby rendering unnecessary both the expenditure of excessive energy and the separation of the oil it is desired to discharge from sea water, washing water, or treated oil.

30 Yet another object of the invention is to present an oil delivery system that offers particular advantages relating to sea-board industries having a centralized control system of mass-production.

35 A still further object of the invention is to provide an oil delivery system of simplified design.

In achieving these and other objects there is provided according to the present invention an oil delivery system wherein, in order to effect the discharge of solidified or semi-solidified oil remaining in a tank after primary delivery of the bulk of the oil therefrom, a nozzle, or nozzles are inserted in the free space within the tank, a certain portion of the oil previously discharged in the primary delivery, or oil of the same kind, but from another source, is heated and directed through the nozzle or nozzles onto the residual oil, which is thereby melted, and rendered easily removable. The system of the present invention offers advantages in that the residual heat of previously discharged oil may be used to effect the removal of residual oil in a tank, that there is no waste of oil, since a tank may be perfectly emptied, and that no extra labour force is required.

55 Types of oil, for the delivery of which the system of the present invention finds application, are such oils as become solidified or semi-solidified, go into a jelly-like condition, or exhibit highly viscous flow characteristics, at ambient temperatures around an oil tank, that is, ambient air temperature, or water temperature, whichever is lower. Examples of such oils, or oily substances, are the animal or vegetable fats or oils such as beef tallow (melting point 35°-50°C), pork lard (melting point 28°-48°C), palm oil (melting point 27°-50°C), palm kernel oil (melting point 25°-30°C), coconut oil (melting point 20°-28°C), or hardened oils or fractionated oils whose melting point temperatures lie in a similar range. Among the mineral oils, for which the system

of the invention is particularly useful, there may be cited high-viscosity crude oils, heavy oils, vaselines, etc. The system is not of course limited to application for the delivery of oil, but may also be used for other non-oily substances possessing high viscosity and liable to form sludges, such as black-strap-molasses.

Nozzles employed for the projection of oil in the system of the present invention are not limited to being any special type, but should preferably have good heat and pressure resistance characteristics. As examples of nozzles that may be employed, there can be cited nozzles as used in known oil tank cleaning means such as the Butterworth Tank Cleaning Machine Toko Mini-Jet Washer, Victor Pyrate Automatic Tank Washer, Maersk-Clean, Toftejorg Tank Cleaning Machine, or Cupper Nozzle, all of which are trade names of products available commercially. A cleaning means such as cited above and having either fixed or portable nozzle portions is provided in a tank, in the vicinity of the tank, or on a jetty, or other unloading point. It is particularly advantageous, but not essential, to mount the cleaning means on a jetty, and to provide portable nozzles, so that any number of vessels may be dealt with from the same point. Also, if the nozzle portions provided are of the rotatable eccentric nozzle type comprising two or more nozzles inclined in different directions, there is no need to provide a special support rod, or similar means, for positioning the nozzles in a tank, but the nozzles may simply be suspended freely inside the tank, and heated oil projected therefrom evenly melts the residual oil. The most suitable number of nozzles for melting residual oil in a tank depends, of course, on the size of the tank. Also, it is evident that the use of rotatable, eccentric nozzles is not essential to the system of the present invention, for it is equally possible to employ, for example, fixed nozzles directed vertically downwards.

There is some variation in temperature to which oil for melting residual oil is heated, depending on the types of oil and on ambient conditions. For the above-cited fats and oils like beef tallow and pork lard, a suitable temperature is generally 70°-90°C. The temperature selected should be one which is economically attained, sufficiently lowers the viscosity of the oil, and which has been selected after consideration of possible deterioration of the characteristics of the oil, and, of course, safety factors, especially in the case of low flash-point oils.

According to the system of the present invention, nozzles for the ejection of heated oil are provided on a normal tanker, or similar vessel, from which oil is to be delivered. A storage tank, pumps, a heater or heaters, strainers, and other conventional items of equipment are provided at the oiling station to which the oil is to be delivered, and the equipment is linked by suitable piping. In the simplest arrangement, the bulk of the oil from a tanker is piped to a storage tank on land, and then a portion of this delivered oil is heated and forced back through pipes connecting to nozzles provided in the ship's hold as described above. The oil is then directed onto and melts the residual oil, and the whole, that is, the residual oil and the oil that has been fed back, is pumped out by the ship's pumps to the storage tank on land. Alternatively, the oil pumped out in the secondary delivery (the residual oil and a portion of the primary delivery oil) may be supplied to a second storage tank on land. Also, the piping between ship's

tanks and storage tanks on land may be equipped as required with filters, strainers, etc., for the elimination of undesirable matter from the piped oil. Also, a heater and pump, for heating and pumping oil for melting residual, may be provided on a vessel instead of on land, and only a storage tank provided on land. If it is not possible, or is difficult, for tankers to approach or anchor near an oiling station, there may be provided barges equipped with heaters and intermediate storage tanks for relaying oil from tankers to storage tanks on land. In all cases, attention should be given to the prevention of heat losses by the provision of adequate piping insulation in the form of asbestos or other suitable material. There should also be equipment such as suitably located oil gages to make it possible to measure and compare the quantities pumped out from a tanker, piped to a storage tank, and piped back to the tanker.

Preferred embodiment of the present invention will now be described, by way of example, with reference to the attached drawings, in which:

FIG. 1 is a schematic diagram showing connection of components employed in an oil delivery system according one embodiment of the present invention;

FIG. 2 is a cross sectional view, on an enlarged scale, showing a portion of FIG. 1, and

FIG. 3 is a similar view of FIG. 1, but showing another embodiment of the present invention.

Before describing the specific embodiments of the present invention, it is to be noted that like parts are designated by like reference numerals throughout the several views of the accompanying drawings.

It is also to be noted that the concept of the application as well as the application can also be applied to any fluid delivery system other than ship's oil tank, for example, to oil firm on land or the like.

Referring now to FIGS. 1 and 2, there are provided a first storage tank 10 provided on land L, a ship's oil tank 11 equipped in a vessel S on sea and a second storage tank 12 provided on land L. In the free space within both the 1st storage tank 10 and ship's oil tank 11 there are suspended with hoses 14, 14 jet-cleaner nozzles 13, 13 of the eccentric double nozzle type which are freely rotating by means of pressured oil supplied through the hoses 14, 14 for directing pre-heated oil upon residual solidified or semi-solidified oil in the tanks 11, 12. The hoses 14, 14 are respectively connected with pipes 15, 15 which meet at a junction connected to a supplying pipe 16 which leads to the lower portion of the second storage tank 12, and in which is provided a supply pump 17, a pre-heater 18 and a check valve 19. The intermediate portion of each hose 14 is, as shown in FIG. 2, suspended detachably on a disc hanger 20 of a saddle 21 provided movably on the upper deck of vessel S or on the ceiling of tank 10 while the pump 17 and heater 18 are provided on land L. The hanger 20 with hose 14 is rotated on occasion by a motor M provided on the saddle 21 to adjust the position of the nozzle 13 in the tank 10, 11. Also, in each tank 10, 11 there are provided a suction pipe 22, one end of which is opened at the lowest portion of the tank 10, 11 to pump oil out in the tank 10, 11, and heaters 23 at middle of the tank 10, 11 to melt oil, as provided in a conventional system of this kind. The suction pipe 22 of the ship's oil tank 11 is connected with a delivery pump 24 provided on the lower deck of vessel S and, then, with a flexible pipe 25 which leads to the upper portion of the second storage tank 12 through a check valve 26, while the other

suction pipe 22 of the first storage tank 10 is connected with a delivery pump 24 provided on land L and, then, with the flexible pipe 25. Between the delivery pumps 24 and the check valve 26, the flexible pipe 25 is connected through a pipe 27 having a check valve 28 to the supplying pipe 16 desposed between the supplying pump 17 and the check valve 16.

The arrangement so far described is operated such that, when the valves 19, 26 are opened but the other valve 28 is closed, and the pumps 17, 24 and pre-heater 18 are driven, oil from the second storage tank 12 is pumped through the pipe 16 by the supply pump 17, heated by the pre-heater 18, and supplied through the pipes 15, 14 to the nozzles 13, from which it is sprayed onto residual oil in the first storage tank 10 and ship's oil tank 11. The residual oil is thereby melted, and together with the oil sprayed thereon by the nozzles 13, is pumped out by the delivery pump 24 through the pipes 22, 25 to the second storage tank 12. On the other hand, when the valves 19, 26 are closed and the valve 28 is opened, oil being pumped out from both the first storage tank 10 and ship's oil tank 11 by the delivery pumps 22 is recirculated through the pipes 22, 25, 28, 16, 15, 14, supply pump 17 and pre-heater 18 to the nozzles 13 in the tanks 10, 11, thus resulting in greater efficiency in the recirculation of relatively high temperature oil. With reference to temperatures and pressures for different oils or fats delivered by the system above-mentioned, in case of beef tallow, for example, the internal temperature of the second storage tank 12 is suitably 60°C, the supply pump 17 pumps at a pressure of 10 kg/cm² and the pre-heater 18 raises the temperature of the tallow to 85°C.

FIG. 3 shows another embodiment of the present invention in which the first storage tank 10 of the previous embodiment shown in FIGS. 1 and 2 is provided in the vessel S' having the first oil tank 11a and a second oil tank 11b, thereby to obtain a system for effecting simultaneous primary and secondary deliveries of oil from a plurality of vessels or from a plurality of tanks in one vessel. In FIG. 3 there is shown a tanker S' and two separate oil tanks 11a, 11b therein. It is supposed that the bulk of the oil in tank 11b is still to be delivered by a pump 24a, and that primary delivery of the oil in tank 11a has been effected, but that secondary delivery of residual oil therein is still to be effected. In this embodiment the piping, valves and other equipment are the same as described in reference to FIG. 1, except that there is only one jet cleaner nozzle 13, which is suspended in the tank 11a, above the residual oil therein, and so the two pipes 15, 15 are unnecessary, and heated oil is supplied directly to the nozzle 13 through the pipe 14.

Operation of the second embodiment is as described above in the first embodiment and when the valves 26, 19 are opened and the valve 28 is closed, stable operation is ensured by regulation of the pump 17 on the pipe 16 through the heater 18, and heat is used with maximum efficiency.

As may be seen from the above description, the present invention provides a rapid, automatic, and economical system for delivering high melting point oil remain-

ing in a tank.

The present invention has been fully disclosed by way of the preferred embodiments thereof. However, it is to be noted that various changes and modifications thereof are apparent to those skilled in the art from the foregoing description with or without reference to the accompanying drawings. Therefore, these and other changes and modifications should be construed as included within the scope of the present invention unless otherwise departing therefrom.

What is claimed is:

1. A system for removing melted and unmelted high melting point oils from a first tank comprising, removal means for removing melted high melting point oil in the first tank, storage tank means having a capacity at least equivalent to said first tank, connected to said removal means for receiving said melted oil delivered by said removal means from the first tank, nozzle means inserted into an open space within said first tank above any unmelted high melting point oil in said first tank for directing oil under pressure onto residual unmelted oil in said first tank, and supply means connected between the storage tank means and the nozzle means, said supply means comprising a pump and a heater for heating oil to a temperature such that the residual unmelted oil remaining in the first tank is melted by the heated oil directed through said nozzle means, whereby the high melting point oil in the first tank is melted so as to be removed by the removal means.

2. A system as claimed in claim 1 in which is provided distribution means for directing the oil removed from the first tank by the removal means to either the storage means or to the supply means without first going into the storage means.

3. A method for removing high melting point oils contained in a tank comprising, the step of providing a portion of the same type of oil as is to be removed and which is at such a temperature that it will melt unmelted oil remaining in the tank, the step of directing said heated oil under pressure onto residual unmelted oil remaining in the tank, whereby the unmelted oil remaining in the tank is melted, and the step of removing melted oil from the tank, and continuously repeating said steps until the unmelted residual oil in the tank is wholly melted and removed from the tank.

4. A method as claimed in claim 3 in which the step of providing a portion of oil the same as the type of unmelted oil to be removed comprises obtaining said portion from a source of supply and heating said portion to such a temperature that it will melt the unmelted oil remaining in the tank.

5. A method as claimed in claim 3 in which the step of providing a portion of oil the same as the type of unmelted oil to be removed comprises using the melted oil removed from the tank in the removing step either mixed or unmixed with oil from a source of supply.
